CHARLES E. REDDIG, OF KEW GARDENS, RICHMOND HILL, NEW YORK, ASSIGNOR TO
GRAYBAR ELECTRIC COMPANY, OF NEW YORK, N. Y., A CORPORATION OF NEW
YORK

COMBINED WASHING MACHINE AND DRIER

Application filed October 8, 1927. Serial No. 224,780.

This invention relates to a combined washing machine and drier.

The principal object of this invention is to provide a compact washing machine for general domestic use in which a drying and a washing operation may be performed in a single tank concurrently. A further object is to dry the laundry by centrifugal force and eliminate the danger to both the user and the laundry by the wringer mechanisms now commonly employed. A further object is to provide a washing machine in which the laundry during the washing process is retained in a loose condition and carried in a continuous path by the wash water, thereby preventing matting, and enabling the ready loosening of dirt from the laundry.

Still a further object is to eliminate any moving parts which, contacting with delicate garments, may injure the same. Another object is to provide a washer in which the cleansing is performed entirely by the action of currents of water containing the desired cleansing agent, such as soap. A still further object is to provide a machine which has a minimum of rotating parts and thereby a machine which is extremely simple and not likely to require adjustment, or repairs.

Fig. 1 is a top view of a preferred form of my combined washing machine and centrifugal drier.

Fig. 2 is a section on line 2—2 of Fig. 1 viewed in the direction of the arrows showing the tank and partition structure, the drier, and the drive therefor.

Fig. 3 is a top view of another machine embodying my invention in which the pump is below the drier and on the drier shaft.

Fig. 4 is a section of this machine along the line 4—4 of Fig. 3 showing the parts in elevation.

Fig. 5 is an enlarged view of the drier mounting in section of the machine of Fig. 3, and Fig. 6 is a partial view of the tank of this machine showing the agitator and agitator casing in section;

Reference being had to the drawings, the cylindrical tank, 10, is supported upon a convenient structure, 11. A motor, 12, is af-

fixed to the supporting structure and below the tank, carrying a pulley, 23, and driving by means of a belt, 24, the pulley, 22, upon the centrifugal drier shaft, 21.

The tank, 10, is divided into two compartments by means of the partition, 15, one of which compartments is adapted to receive the laundry to be washed, whereas in the other compartment, 26, the centrifugal drier mechanism, 14, is disposed. The partition is S shaped, or any other convenient curved shape to give the wash water a continuous current path without abrupt breaks or bends. The partition is perforated, 17, below the water line and at the end remote from the orifice, 39 shown in Figs. 1, 3 and 6.

The centrifugal drier is formed in the shape of a hollow inverted cone having an inwardly projecting rim, 18, at the top. Immediately below this rim and above the water level of the machine, a series of openings, 19, are provided permitting the draining of the water extracted from the laundry which is being dried back into the tank. On the outer surface of the rotating container are a convenient number of vanes, 16, projecting from the portion of the container submerged in the wash water and serving to give it a continuous current, as indicated by the arrows in Fig. 1. The rotating container, 14, is rigidly mounted upon and supported by the collar, 27, keyed to the shaft, 21. The closure member, 28, is welded or riveted to the bottom of the tank and is integral with the shaft bearing, 29. The lower end thereof is conveniently threaded and packing provided therebetween and the nut, 30, conveniently made of a size to be tightened by hand.

In a variation of my invention, shown in Figs. 3, 4 and 5, the centrifugal drier is formed with a re-entrant base, 31, with its central portion extending upwardly to above the water line. This re-entrant portion is 95 rotatably supported upon and by the upwardly projecting portion, 32, of the agitator, 33. The agitator is fixed to the shaft, near its upper end and rotates therewith. The lower end, 34, is rotatably supported 100

upon the sleeve, 35, which extends through the base of the tank and into the compartment, 26. A clutching device, 36, is provided at the extreme upper end and threaded end of the shaft, the stop, 37, limiting the upward movement of the clutching knob, 36.

The agitator blades, 33, are suitably housed in a casing, 38, at the bottom of the centrifugal drier compartment and are designed to discharge the water through the orifice, 39. The circular opening, 40, in the agitator casing at the top thereof permits the continuous use of the water in the tank.

In the operation of the machine, the tank is filled with water to a level below the perforations, 19, in the combined drier and agitator. The batch of laundry to be washed is placed in the washing compartment and thereupon the motor is started. The container, 14, will agitate or impel the water by means of vanes, 16, causing a circulation of the water in the direction of the arrows shown in Figs. 1 and 3. At the same time any laundry which has been washed in a previous batch and which has been put into the container, 14, is whirled around at a speed sufficient to drive the water upwardly along the sides of the container and through the perforations, 19, draining back into the wash water in the tank. Thus a simultaneous drying of the clothes may be obtained while another batch is being washed.

In the alternative arrangement if there is no laundry to be dried in the centrifugal drier the clutch, 36, is given a few turns by hand thus releasing it from the reentrant portion, 31, of the container. Upon starting the motor the clutch and shaft as well as the agitator will rotate while the drier remains stationary. Thereafter for the washing of the second and subsequent batches of laundry, the clutch is given a few turns in the opposite direction and the container is clutched to the shaft and whirled around therewith at a speed sufficient to extract the water from the clothes.

What is claimed is:

1. In a washing machine, a tank, a perforated vertical partition therein and extending across the same and dividing it into two compartments, one of which is adapted to receive a batch of laundry to be washed, an impeller mounted in the other compartment adapted to cause a continuous circulation of the water within the tank, said impeller having a recess adapted to receive a batch of washed laundry, and a means for rotating said impeller at a rate of speed sufficient to extract the water from the laundry within the impeller.

2. In a washing machine, the combination of a wash tank, a receptacle having side

walls, the side walls of said receptacle being perforated near its top only, means for rotating said receptacle at sufficient speed to extract surplus water from clothes placed therein, and discharge this water up the walls and out of the perforations by centrifugal force, and agitator vanes mounted upon the exterior surface of said receptacle below the level of the holes.

3. In a centrifugal extractor for removing excess water from clothes, the combination of a tank, a receptacle in said tank having outwardly sloping side walls, means for rotating said receptacle at sufficient speed to extract surplus water from clothes placed therein and discharge this water over the edge of the receptacle by centrifugal force, and agitator vanes upon the outside of the side walls of said receptacle.

4. In a washing machine, the combination of a cylindrical tank in which clothes are washed, a cylindrical receptacle mounted eccentrically within said tank, means for rotating said receptacle to expel water by centrifugal force from clothes placed therein, and agitating means rotatable about the axis of, external to and driven simultaneously with the receptacle by said means for agitating the water in said tank for washing clothes placed therein.

5. In a washing machine, the combination of a tank, an S-shaped vertical partition separating said tank into two parts and having an opening at one end and perforations at the other to permit the circulation of fluid contained in the tank, a rotatably mounted container in one part carrying impeller blades externally thereof and adapted by its rotation to cause a fluid in the tank to circulate, openings in said container adjacent the top thereof only, said openings so located that any fluid in the container will be expelled by centrifugal force during rotation and means to rotate said container.

6. In a washing machine, the combination of a tank, a vertical partition separating said tank into two parts, openings in said partition, a rotatably mounted container in one of said parts, impeller means mounted on said container externally thereof and adapted to circulate fluid in said tank, openings in said container adjacent its upper end only, through which any fluid in the container will be expelled by rotation of the container and means to rotate the container.

7. In a washing machine, the combination of a cylindrical washing tank, a centrifugal drying vessel, eccentrically mounted in said tank, impeller means for the contents of said washing tank rotatable around the axis of said drying vessel externally thereof and driving means for said drying vessel and said impelling means.

8. In a machine of the character described,

5 a cylindrical tank, an eccentrically mounted centrifugal drier in said tank, impeller means for circulating fluids in said tank concentrically mounted with said drier, external thereto and means for driving said drier and impeller means.

10 9. In a machine of the character described a washing tank, a centrifugal drier in said tank mounted toward one side of said tank, impeller means for circulating fluid throughout said tank and means for driving said drier and impeller.

15 In witness whereof, I hereunto subscribe my name this 28 day of Sept, 1927.

CHARLES E. REDDIG.
